COMBINATION LIGHTING FIXTURE AND
CURTAIN HOLDER

William J. Mollner, Pittsburgh, Pa.

Application August 10, 1950, Serial No. 178,650

4 Claims. (Cl. 240—2)

1

This invention is for a lighting fixture, and especially a lighting fixture intended to provide in addition a support for curtains and/or drapes. Interior decorators are not infrequently bothered by the fact that the source and quality of light in a room at night is quite different from that in the day time. Whereas the light during the day is obtained principally from windows, the light at night is obtained from fixtures or lamps scattered about the room. This often interferes with the most effective interior decoration because a compromise must be made to suit both conditions of illumination. Moreover the location of furniture must be very largely determined by the location of the windows on the one hand and the lighting fixtures and lamps on the other. In addition to this, curtains or drapes which may be fully visible both outside and inside the house during the day may appear somewhat drab or unattractive when viewed at night against or with conventional lamps or lighting fixtures. Additionally the location of lamps and lighting fixtures remote from the windows often, if not generally, silhouettes the occupants of the room between the window and the light source, causing the occupants of the room to be plainly visible to passers-by at night if the room be close to the walk at street level.

The principal object of the present invention is to provide the interior decorator or householder with a lighting fixture that will eliminate or minimize many of the foregoing difficulties and provide a new and attractive illumination for rooms and drapes and reduce or eliminate to considerable extent the need for chandeliers, wall brackets, and various floor or other lamps. The invention further provides a fixture which enables furniture to be so positioned that an arrangement which is satisfactory for daylight is also satisfactory for artificial illumination, and there is no need at night for example, for a reading chair to be moved from a point near the window to a point near a lamp or lighting fixture. These and various objects and advantages are obtained by my invention, including novel and attractive illumination effects.

According to my invention there is provided a supporting frame or panel which is preferably adjustable to various window sizes, and which may be used to take the place of a cornice or rod for drapes, and which may itself serve as a support for drapes. This structure is provided with adjustable brackets to receive and hold a fluorescent tube lamp which is concealed by the panel from direct vision. Additionally the fix-

2

ture may support a third rod and also support a reflector and/or light-transmitting screen so as to enable different colored effects or different indirect lighting effects to be secured.

5 My invention may be more fully understood by reference to the accompanying drawings which illustrate one embodiment of my invention, and wherein:

Fig. 1 is a perspective view of the fixture in 10 the position in which it is adapted to be placed at the top of a window frame;

Fig. 2 is a top plan view of the fixture shown in Fig. 1;

Fig. 3 is a transverse section through the fixture in substantially the plane of line III—III of Fig. 2;

Fig. 4 is a similar section in the plane of line IV—IV of Fig. 2; and

Fig. 5 is a similar view in the plane of line V—V 20 with the fluorescent tube lamp removed therefrom.

Referring to the drawings, the fixture is preferably comprised of two main sections designated 2 and 3, which are formed of any suitable material, burnished aluminum being highly satisfactory, although any other suitably finished metal may be used. Each of the two sections has a wide flat front panel portion designated 2a and 3a respectively. The top and bottom edges of the section 2 are turned over on the inner face of the fixture to provide retaining flanges 2b and 2c. The corresponding edges of the section 3 are likewise turned inwardly to provide flanges 3b and 3c, the dimensions being such that one section slidably or telescopically engages the other in a manner similar to that frequently used in conventional flat curtain rods. In the present drawings the member 3 is shown as telescoping within the member 2, and the turned-over flanges 2b and 2c of the member 2 form guides for the contacting portions 3b and 3c of the section 3.

The free ends of the members 2 and 3 are formed with wing or bracket portions 4 and 5 respectively, which are turned at right angles 45 to the portions 2a and 3a. At the inner ends of these bracket portions 4 and 5 are oppositely-turned flanges or pads 6 and 7 respectively, which are designed to be placed against the top of the window frame and secured in place thereon.

The flanges 6 and 7 are shown as being provided with key-hole slots so that the fixture can be hung on screws suitably located at each side of the top of the window frame. When the device is positioned on the window frame, the wings 4 and 5 extend forwardly horizontally from the

plane of the window frame while the front panels 2a and 3a of the telescoping sections extend across the top of the window frame, much the same as an ordinary flat curtain rod, although the parts 2a and 3a are much wider from the lower edge to the top edge than the conventional flat curtain rod. This width, while not critical, should be of the general order of three inches or somewhat more, in order to provide a screen or shield behind which the fluorescent tube lamp hereinafter described is located. It should be substantially wider than the diameter of the tubular light source.

Each of the wings 4 and 5 is provided with an aligned hole 8 to receive the ends of a curtain rod 9. In Figs. 3 and 4 I have illustrated these holes 8 as being also in the form of so-called key hole openings with the larger portion of each opening at the top. With this arrangement the ball or other large terminal on a curtain rod may be passed through the opening, and then the curtain rod lowered, and be thereby restrained against endwise movement.

The inwardly-turned flanges 2b and 2c not only provide sliding contact surfaces for the telescoping sections, but they also provide slideable trackways for lamp terminal brackets designated generally as 10. These brackets as shown in the drawings, have a vertical strip 11, the ends of which are slidably received in the channels formed by the overturned edges 2b and 2c and 3b and 3c. A set screw 12, which may be of any suitable kind, and which is here shown as being provided with a screw slot for engagement by a screw driver, is threaded through this strip, and by tightening up on the screw, the strip may be frictionally retained from sliding endwise in the fixture. Each of the strips 11 has a rearwardly-extending horizontal arm 13 which in turn supports a conventional lamp socket 14 for receiving a conventional fluorescent tube which usually has two contact prongs at each of its ends.

As shown in Fig. 5, the terminals are formed as insulating bodies 14 and have the usual arrangement of slots 15 for the reception of the terminal pins on a fluorescent tube. In the drawings I have not shown the flexible cords through which current is supplied to the contacts within the terminals 14, as this wiring may be conventional, and forms no part of the invention, and is well known to those skilled in the art. Where the fluorescent tube is of the type requiring a starting control, the conventional starting control box may be located at any convenient place either in the curtain fixture or on the slot adjacent the window where the curtain fixture is located. The wires can usually extend up along the window frame and are concealed by the curtains or drapes, or are at most only very inconspicuous. By having the fluorescent tube sockets movable longitudinally along the fixture, luminous tubes of any selected length can be used and standard length tubes can at all times be accepted and be brought to a centered position on the fixture.

It is desirable to provide for adjusting the length of the bracket in order to avoid making the fixtures in an infinite range of sizes, and it is also desirable to so support the fluorescent tubes that they can be always centered in the fixture midway between the ends, and so that long or short fluorescent tubes may be used as the decorator or householder may choose.

The arms 13 on the brackets for supporting the lighting fixtures are of such length that the

fluorescent tube, designated 16 in the drawings, will be relatively close to the inner face of the panels 2a-3a, and will be about midway between the top and bottom edges thereof. By reason of this and the greater width of the panel, the tube is concealed from direct vision, except when one is practically under the lighting fixture, and the tube is high enough so that when the fixture is properly placed on a window frame, the tube is not ordinarily seen by one passing along outside the house, unless again the passer-by should be almost under the window.

In order to give a desired color and quality to the light, there is provided a second pair of 15 slidably adjustable brackets 17 which, however, do not need to be provided with set screws, as friction may be relied upon to hold them in place. These brackets 17 have a rearwardly-extending curved supporting arm 18. One of the 20 brackets is located near each end of the fixture. It serves to support a concaved member 19 which may be either a transparent colored screen or a translucent colored screen, or which may be frosted or of milk-like translucency, or which 25 may be partly or wholly silvered to provide either a reflector or a partial reflector.

The member 19, depending on its character and quality, may be formed of plastic, glass or metal. Relatively thin sheet plastic material is 30 preferably used as it is inexpensive and can be easily cut to any desired length with a pair of scissors.

As viewed in Fig. 4, the member 19 might for example be silvered in the part spanned by the 35 bracket marked with A, and a similar strip along the opposite edge might also be silvered, while the intervening area could be colored or frosted.

In use, the fixture is placed at the top of the 40 window frame the same as a conventional curtain rod or cornice, care being taken to place it high enough so that the luminous tube light will not be below the lower edge of the top of the window frame. Curtains may be placed on the curtain 45 rod in the usual way, and hung in front of the window. The luminous tube lamp is placed in position after the terminal contact members have been properly adjusted, and a colored screen or reflector member 19 selected to suit the taste of the home owner or interior decorator is placed on the supports 10. Drapes may be hung directly 50 on the cross bar of the fixture by the use of conventional hooks or in any other accepted fashion.

When the device is in use, brilliant illumination 55 of course is provided by the fluorescent tube. The fixture being close to the ceiling, much of the light is reflected to the ceiling and diffused through the room. Other light is directed down against the curtains, and of course is reflected by the curtains into the room, and is otherwise diffused into the room. Very satisfactory diffusion of light is obtained, and the location of the illumination is much the same as that which enters the room from natural daylight. Therefore whether it is daylight or whether artificial 60 light is being used, the curtains are illuminated and the light diffuses through the room from the same general direction and the furniture set appropriately for daylight is likewise appropriately placed for the artificial illumination. Floor 65 lamps can be to a large measure eliminated, which makes floor space available for other furniture, a feature which is quite desirable in small rooms, and chandeliers and lighting fixtures can likewise be eliminated. While, for decorative 70 purposes only, table or floor lamps may con-

tinue to be provided, the actual need for them is substantially reduced.

The fixture at the same time enables fluorescent lighting to be used in rooms where usual fluorescent types of lighting fixtures would appear out of place, or appear to be in bad taste. At the same time, while giving diffused illumination and all of the foregoing advantages, the fixture is relatively inexpensive and can be installed at a cost much less than that required for built-in or suspended types of fluorescent tube lighting.

Instead of accentuating the light source as do most sources of artificial illumination, one sees curtains and/or drapes as usual, with a diffused light at the windows when the room is artificially lighted using my fixtures, and attention is focused, as it should be, on drapes, curtains and the contents of the room.

It will also be seen that because the light is diffused down across the curtain, the outsider sees the curtains illuminated in much the way that a person in the room sees them, but the persons in the room are not silhouetted between the light source and the window, as is the case with present conventional indoor lighting.

The advantage of using telescoping sections in assembling the fixture is of course to enable a ready-made standard fixture to be adapted to a range of window sizes, but the fixtures can be otherwise formed in fixed sizes, or be custom-made.

While I have illustrated and described one embodiment of my invention, it will be understood that various changes and modifications may be made therein, and that specific elements may be otherwise constructed within the contemplation of my invention and under the scope of the following claims.

I claim:

1. A curtain fixture having a panel portion formed of two sections each having its top and bottom edges rolled over to form channel portions along the inner face thereof, said sections being telescopically fitted together, each section having a bracket portion at its end by means of which it may be supported on a window frame, and a light-supporting terminal on the inner face of each section, said terminal having a base portion which is engaged in the channel portions of the section on which it is mounted, and means for adjustably clamping said terminals in position.

2. A curtain fixture having a panel portion formed of two sections each having its top and bottom edges rolled over to form channel portions along the inner face thereof, said sections being telescopically fitted together, each section having a bracket portion at its end by means of which it may be supported on a window frame, and a light-supporting terminal on the inner face of each section, said terminal having a base portion which is engaged in the channel portions of the sections on which it is mounted, means for adjustably clamping said terminals in position, and a bracket element at the rear face of each panel for supporting a light-modifying screen in position below a tubular lamp when a tubular lamp is engaged in said terminals.

3. A curtain fixture for windows comprising a length adjustable front panel formed in two sections with a window frame attaching bracket at the end of each section, said panel sections being telescopically united by interlocking channel flanges positioned at the top and bottom on the back of each section, tubular lighting element terminals mounted behind said panels in said panel flanges, a lighting element mounted in said terminals, brackets for supporting a light-modifying screen mounted behind said panels and adjustably secured in the panel flanges, and rearwardly-extending arms on the screen brackets positioned below the lighting element to support the modifying screen, said panels, terminals and screen supporting brackets being adjustable longitudinally of the panels to position the lighting tube and screen for windows of different lengths.

4. The curtain fixture defined in claim 3 in which a curtain rod is mounted between the window frame brackets in a position parallel to and behind the panel and between the lamp and the window frame.

WILLIAM J. MOLLNER.
